SPINAL ADJUSTMENT APPARATUS

Leon A. Politis, North Adams, Mass., assignor to
C. W. Ransom, Pittsfield, Mass. and himself

Application April 9, 1936, Serial No. 73,551

13 Claims. (Cl. 128—69)

This invention relates to certain new and useful improvements in spinal adjustment apparatus.

An object of the invention is to provide a mechanical device for reducing or removing a luxation of the spinal vertebrae.

Another object of the invention is to provide a spinal adjustment apparatus that may be set whereby an operator may make an adjustment 10 with a stroke having a definite and predetermined direction and magnitude.

A further object of the invention is to provide apparatus of the foregoing character whereby the operator may repeat with precision the forces 15 applied in a given treatment, the apparatus being capable of adjustment whereby the direction and the magnitude of the forces as required may be varied.

A further object of the invention is to provide 20 apparatus for spinal adjustment in which the adjustments may be made with extreme rapidity and in a manner whereby the applied pressure is completely removed instantly after reaching the maximum, thereby permitting the innate 25 forces to determine the ultimate position of the vertebrae.

With the above and other objects in view that will become apparent as the nature of the invention is better understood, the same consists 30 in the novel form, combination and arrangement of parts hereinafter more fully described, shown in the accompanying drawings and claimed.

In the drawings:—

35 Figure 1 is a vertical longitudinal sectional view of the spinal adjustment apparatus;

Figure 2 is a fragmentary horizontal sectional view taken on line 2—2 of Figure 1, showing devices for accomplishing an angular adjustment 40 of the head and also rotary adjustment thereof;

Figure 3 is a cross-sectional view taken on line 3—3 of Figure 1;

Figure 4 is a cross-sectional view taken on line 4—4 of Figure 1;

45 Figure 5 is a detail sectional view taken on line 5—5 of Figure 1 of the plunger or contact member;

Figure 6 is a detail sectional view taken on line 6—6 of Figure 1, showing the cam and clutch 50 device for the operation of the drum upon which the operating cable is wound;

Figure 7 is a horizontal sectional view taken on line 7—7 of Figure 1;

Figure 8 is a fragmentary plan view of the up- 55 per end of the standard, showing the indicator

for determining horizontally swinging adjustments of the laterally extending arm;

Figure 9 is a fragmentary side elevational view of the upper end of the standard; and

Figure 10 is a fragmentary side elevational 5 view showing the indicator associated with the inner pivoted end of the head of the apparatus.

Referring more in detail to the accompanying drawings and particularly Figure 1, the reference character 15 designates a standard or support 10 having an arm 16 projecting laterally of the upper end thereof, the arm 16 carrying a head 17 at its free end and from which head 17, a plunger or contact member 18 depends.

The standard 15 comprises a tubular member 15 19 having an enlarged base 20 that carries a plate 21 to facilitate mounting of the tubular member 19 upon the work table, bench, floor or other support.

The arm 16 comprises a tubular elbow defined 20 by a horizontal arm 22 and a depending tubular leg 23 that telescopes into the tubular member 19 of the standard 15. Means is provided for effecting vertical adjustment of the tubular leg 23 in the tubular member 19 with devices for 25 indicating such adjustment and as shown in Figures 1, and 7 to 9, the upper end of the tubular member 19 is fashioned to provide a clamp and a support for a pinion, the clamp construction comprising a pair of semi-circular strap mem- 30 bers 24 and 25, the latter comprising a section 26 hinged thereto at 27 with cooperating lugs 28 and 29 projecting from opposite ends of the strap members 24 and 25. A length of semi-circular

rack teeth 30 extends partly around the side of 35 the tubular leg 23 to be engaged by a pinion 31 carried by a pin 32 journalled in the lugs 28, the pinion being operated by the handle 33 on the pin 32. When the tubular leg 23 has been properly adjusted relative to the tubular mem- 40

ber 19, the hinged clamp member 26 carried by the strap 25 is tightened by the screw 34 threaded through the lugs 29 and operated by the handle 35, the clamp member comprising the straps 24 and 25 being moved into binding engagement 45

with the tubular leg 23. To determine the length of vertical adjustment of the tubular leg 23 in the tubular member 19, the leg 23 adjacent its upper end is provided with circumferentially ex- 50

tending gage lines 36 shown more clearly in Figure 9 with which the arrow or indicator 37 at the upper end of the tubular member 19 is asso- 55

ciated. To determine angular adjustments in the horizontal plane of the arm 22, a graduated dial 38 shown more clearly in Figures 1, 8 and 9 55

is carried by the end of the arm 22 extending over the leg 23, the indicator associated with the dial comprising a rod 39 having a pointer 40 cooperating with the dial, the rod being carried by a ring 41 rotatable upon the upper end of the leg 23 with the lower end of the rod 39 extending through guide members 42 carried by the tubular member 19 for restraining the rod and indicator 40 against movement during horizontally swinging movements of the arm 22. The indicator rod 39 extends downwardly between the clamp lugs 29 as shown in Figure 7.

The arm 16 embodying the horizontal arm section 22 also includes an arm section 43 that telescopes in the arm 22 and as shown in Figures 1 and 2, the arm section 43 is both rotatable and longitudinally adjustable relative to the arm 22 with means for holding the two arms in adjusted position. A clamp member 44 is located at the free end of the arm 22, being hinged to the arm as at 45 and bindingly engaged with the arm 43 by means of the clamping screw 46. Cross-gage lines 47 are formed on the arm 43 as shown in Figure 2 and with which the indicator finger or arrow 48 carried by the arm 22 cooperates for determining rotary and longitudinal adjustment of the arm 43 relative to the arm 22. As shown in Figure 1, the arm 43 is of tubular formation and the end thereof projecting from the arm 22 is enlarged and cut away to provide a support substantially U-shaped in cross-section, having a bottom wall 49 and side walls 50 as shown in Figure 3, outwardly offset extensions 51 being carried by the side walls 50 as shown in Figures 2 and 4. The head 17 carrying the contact member or plunger being pivotally mounted between the wall extensions 51 for adjustment to various angular positions.

The head 17 comprises a block body 52 carrying a receptacle 53 at the upper side thereof with a removable cover 54 and a pair of legs 55 projecting from a side wall of the receptacle 53 for pivotal mounting between the side wall extensions 51. A pinion 56 is formed on the inner face of the free end of each side leg 55 of the casing 53 and a pin 57 extends through the pinions 56 and keyed thereto legs 55 and side wall extensions 51 for the pivotal mounting of the head 17. A rack bar 58 is slidably mounted upon the bottom wall 49 of the support at the outer end of the arm 43 and normally extends beyond the bottom wall for engagement with the pinions 56. Angular adjustments of the head 17 are accomplished by moving the head on the pivot pin 57, this action causing the pinions 56 to slide the rack bar 58 between the side walls 50 of the support and to hold the head 17 in its shifted angular position, means is provided for arresting movement of the rack bar 58. As shown in Figures 1 to 3, the rack bar 58 is provided with a longitudinally extending slot 59 through which the screw pin 60 extends, one end of the screw pin threading into an opening in a side wall 50 of the support, the opposite side wall 50 having a slotted opening therein to accommodate the mounting of a clamping bar 61 that is engaged with the rack bar 58 and through which the screw pin 60 extends. A collar 62 is carried by the pin 60 for engagement with the clamping bar 61 for moving the same into binding engagement with the rack bar 58 and to clamp the latter against movement between a side wall 50 of the support and the clamping bar. An operating handle 63 is carried by the screw pin 60. The degree of angularity of the head

17 and contact member 18 is shown on an indicator (see Figures 2, 4 and 10) comprising a pointer 64 carried by a projecting end of the pin 57 and cooperating with a circular series of graduations 65 on the adjacent side wall extension 51.

A part of the operating mechanism for the plunger or contact member 18 is carried by the head 17 and casing 53 thereof and as shown in Figures 1 and 2, the body portion 52 of the head 17 is provided with an axial bore 66 through which the plunger rod 67 rotatably and slidably extends. The upper end of the shaft 67 is normally disposed midway the upper and lower ends of the casing 53 with a pair of grooved wheels 68 and 69 fixed thereto in vertically spaced relation, the upper terminal end of the shaft 67 having a disk 70 fixed thereto above the grooved wheels 68 and 69. The shaft 67 is normally held at its limit of upward movement by means of the coil spring 71 extending between the disk 70 and the top wall 54 of the casing 53. A thrust movement is adapted to be imparted to the shaft 67 and contact member 18 carried thereby and also a partial rotary movement, the shaft 67 being initially rotatably set and then rotated to zero position during the thrust movement imparted to the shaft. As shown in Figure 1, the upper end of the shaft 67 has a key socket 72 therein that receives the key end 73 of a shaft 74 that projects through an opening in the top wall 54 of the casing 53 with a disk head 75 upon the upper end of the shaft 74 that carries a pointer 76 working over a dial on the top face of the casing cover 54. The operating means for imparting thrust movement to the shaft 67 includes a cam 77 fixed to a shaft 78 journalled in bearings 79 in the head casing 53, the cam being engaged with the disk 70 as shown in Figure 1 for limiting upward movement of the disk and shaft 67. A coil spring 80 extends between the shaft 78 and wall of the head casing 53 for normally holding the cam 77 in the position shown in Figure 1.

The contact member 18 as shown in Figures 1 and 5 comprises a tubular member 81 having a key 82 at one end to be received in a key socket 83 in the lower end of the shaft outwardly of the block body 52 of the head 17 and to be retained therein by a spring clip 84. A stem 85 slidably projects through an opening in the lower end of the tubular member 81 and carries a cushion block 86 for body contact at its lower end. The inner upper end of the stem 85 carries a block 87 provided with lateral pins 88 projecting through side slots 89 in the tubular member 81 to prevent rotary movement of the block 86 relative to the tubular member, the stem 85 and block 87 carried thereby being normally held at their limit of lowered movement relative to the tubular member 81 by means of a coil spring 90 within the tubular member that is interposed between the block 87 and floating block 91, midway the ends of the tubular member. A relatively stronger thrust spring 92 is arranged in the upper end of the tubular member 81 between the upper closed end thereof and the floating block 91 and is of the desired pressure or tension for imparting a predetermined thrust, figured in pounds, to the cushion block 86. It is to be understood that a plurality of contact members 18 is provided with thrust springs 92 of various tension so that the desired thrust pressure may be imparted to a cushion block 86.

Thrust movements may be imparted to the

shaft 67 by electrical, pneumatic or hydraulic means and for purposes of illustration, mechanical devices are shown and as illustrated in Figures 1, 2 and 6, a cable drum 93 is journaled in the enlarged base 20 of the standard 15, the drum 93 having a cable 94 wound thereon that extends upwardly through the standard 15, over a pulley 95 at the upper end of the standard to be directed through the arm 16. The cable 94 extends under a guide pulley 96 journaled on a shaft 97 that extends between the side wall extensions 51 as shown in Figure 2 and over a guide pulley 98 carried by the shaft 57, the free end of the cable 94 being attached to a bar 99 slidably in a guide 100 within the head casing 53. A cross-head 101 is carried by the forward end of the slide bar 99, the cable 102 attached to one end of the cross bar 101 passing partly around the grooved wheel 68 and anchored thereto while the cable 103 attached to the other end of the cross bar 101 passes around the opposite side of the grooved wheel 69 and is anchored thereto. A cable or cord 104 is attached at one end to the inner end of the slide bar 99, the same passing over a pulley 105 and attached at its other end to the shaft 78 for rotating the shaft 78 and cam 77 carried thereby against the tension of the spring 80. The operating means for the cable drum 93 includes a pedal bar 107 pivoted within the enlarged base 20 of the standard 15 and projecting through a slotted opening 108 in a side wall of the base, the inner end of the pedal bar 107 being pivotally supported upon a shaft 109 that supports the cable drum and having a cam portion 110 engaged with a cam member 111 for effecting movement of the cam 110, carrying clutch teeth 112 into engagement with clutch teeth 113 on the adjacent end of the cable drum 93. The pedal bar 107 is returned to its normal position after operation by means of the coil spring 114 and said cable drum 93 is returned to its normal position by means of the spring 115 associated therewith as shown in Figure 1.

While the apparatus disclosed herein is capable of adjusting the entire vertebrae system of the spinal column, the same has been primarily designed to effect adjustment of luxations present in the atlas and axis at the end of the spinal column and at the base of the skull. In the practice of chiropractic or adjustment of the spinal column of the human body such treatments have heretofore been made by hand to free the impinged nerves that cause deranged functions. When the hands are alone used, to accomplish such adjustment, it is impossible to impart the exact desired thrust in precisely the direction required to remove the displacement of the articular joint or vertebrae. The apparatus disclosed in this application is designed to impart the exact degree of thrust pressure necessary to overcome an impingement and also to impart the desired twist simultaneously with the thrust action. While any of the vertebrae of the spine may become displaced, and may even cause a curvature, it is believed that nerve impingement is caused primarily by subluxations or displacements of the first and second cervicals, known respectively as the atlas and the axis, adjoining the base of the skull. The present invention was therefore designed for adjusting the atlas and axis. The apparatus may be adjusted for thrust and torque contact with various points on either cervical. The points of contact preferred for use in most cases are the right and left trans-

verse process on the atlas, and the rim of the atlas between the spinous process and either transverse process; and the spinous process of the axis.

The person to be treated is placed on a table or other support and the apparatus adjusted with the cushion block 86 engaged with the determined part of the body and the desired pressure of such engagement is determined by the mark or indicator 85a on the plunger stem 85 as shown in Figure 1 that moves upwardly into the lower end of the tubular member 81 with the block 87 on the upper end of the stem causing a compression of the relatively weak spring 90. The apparatus is adjusted as to height and angularity and when it is desired to impart a partial revolution to the cushion block 86, simultaneously with thrust movement imparted thereto, the shaft 67 is partially rotated to the desired degree by the disk head 75 on the upper end of the smaller shaft 74. The rotatable adjustment of the shaft 67 reduces slack in one of the cables 102 or 103 and increases slack in the other cable. When the cable drum 93 is operated by the pedal 107, the cable 94 that has the cable 104 attached thereto operates the cam 77 against the tension of the spring 80 to lower the disk 70 and shaft 67 by thrust movement, the taut cable 102 or 103 simultaneously effecting a partial revolution of the shaft 67 and contact member 18 carried thereby. The shaft 67 and contact member 18 are lowered with a snap-thrust movement to effect the adjustment on the vertebrae of the patient and the spring 71 immediately elevates or restores the shaft 67 and contact member 18 to its normal position and at this time, the flat side of the cam 77 is engaged with the edge of the disk 70 and the shaft 67 returned by rotation to its zero position during thrust movement. To re-set the contact member, the hand lever 116 shown in Figure 2 as projecting through a wall of the casing 53 and pivotally mounted therein as at 117 has the leg 118 thereof engaged with a lug projection 119 on the disk 70 whereby the disk may be manually lowered by the re-set lever 116 to position the disk 70 below the engaged flat face of the cam 77 whereupon the spring 80 rotates the shaft 78 and cam to restore the same to the position shown in Figure 1.

It will be noted that precise adjustments may be repeated and be exact as to thrust torque and direction, or any of these factors varied by any desired degree to be determined by the gages associated with the adjustable elements. By the reading of an X-ray photograph, or by other means of diagnosis, the several gages of the apparatus may be initially set to give the required adjustment, the patient being definitely located relative to the apparatus. Also the apparatus may be arranged in duplicate so that simultaneous adjustments may be made on both transverse processes, one transverse process and the spinous, or any two points of a given vertebrae, or on a point on one vertebra and a point on the adjacent vertebra.

From the above detailed description of the invention, it is believed that the construction and operation thereof will at once be apparent, and while there is herein shown and described the preferred embodiment of the invention, it is nevertheless to be understood that minor changes may be made therein without departing from the spirit and scope of the invention as claimed.

I claim:—

1. In a chiropractic machine, a standard, a

- horizontal arm having a leg vertically and rotatably adjustable in the standard, the arm comprising rotatably adjustable telescoping sections, a head having a horizontal pivotal connection with the outer end of the arm and a tensioned thrust member depending from the head and detachably connected thereto.

2. In a chiropractic machine, a standard, a horizontal arm having a leg vertically and rotatably adjustable in the standard, a head adjustably carried by the outer end of the arm and a thrust member depending from the head, means for imparting a thrust and rotative movement to the thrust member, including a cam engaged with the thrust member and a manually operable cable having branches respectively engaged with the cam and thrust member.

3. In a chiropractic machine, a standard, a horizontal arm having a leg vertically and rotatably adjustable in the standard, the arm comprising rotatably adjustable telescoping sections, a head having a horizontal pivotal connection with the outer end of the arm and a thrust member depending from the head, means for imparting a thrust and rotative movement to the thrust member including a powered cable operatively connected to the thrust member, and the body engaging part of the thrust member being detachably engaged with the latter.

4. In a chiropractic machine, a standard, a horizontal arm having a leg vertically and rotatably adjustable in the standard, a head adjustably carried by the outer end of the arm and a thrust member depending from the head, and means for imparting a thrust and rotative movement to the thrust member, the horizontal arm including adjustably rotatable and extensible telescoping sections, the head being pivotally supported on the outer section and the thrust member being axially and rotatably movable in the head.

5. In a chiropractic machine, a standard, a horizontal arm having a leg vertically and rotatably adjustable in the standard, a head adjustably carried by the outer end of the arm and a thrust member depending from the head, means for imparting a thrust and rotative movement to the thrust member, including a cam engaged with the thrust member and a manually operable cable having branches respectively engaged with the cam and thrust member, the horizontal arm including an adjustably rotatable and extensible section, the head being pivotally supported on the extensible section and the thrust member being axially and rotatably movable in the head.

6. In a chiropractic machine, a standard, a horizontal arm having a leg vertically and rotatably adjustable in the standard, a head adjustably carried by the outer end of the arm and a thrust member depending from the head, means for imparting a thrust and rotative movement to the thrust member, including a cam engaged with the thrust member and a manually operable cable operatively connected with the cam and thrust member, a tensioned winding drum for the cable, a cam and clutch device for rotating the drum and the connections between the cable and the cam and thrust member including a cable extension from the aforesaid cable attached to the cam, a pair of grooved wheels fixed on the upper end of the thrust member and a pair of auxiliary cables attached to the aforesaid cable and respectively attached to the two grooved wheels and wound thereon from opposite directions for imparting reverse directions of rotation to the thrust member.

7. In a chiropractic machine, a standard, a horizontal arm having a leg vertically and rotatably adjustable in the standard, a head adjustably carried by the outer end of the arm and a thrust member depending from the head, means for imparting a thrust and rotative movement to the thrust member, and the body engaging part of the thrust member being detachably engaged with the latter, a manually operable cable operatively connected with the thrust member, a tensioned winding drum for the cable, a cam and clutch device for rotating the drum and the connections between the cable and thrust member including a pair of grooved wheels fixed on the upper end of the thrust member and a pair of auxiliary cables attached to the aforesaid cable and respectively attached to the two grooved wheels and wound thereon from opposite directions for imparting reverse directions of rotation to the thrust member.

8. In a chiropractic machine, a standard, a horizontal arm having a leg vertically and rotatably adjustable in the standard, a head adjustably carried by the outer end of the arm and a thrust member depending from the head, means for imparting a thrust and rotative movement to the thrust member, including a cam engaged with the thrust member and a manually operable cable operatively connected with the cam and thrust member, the horizontal arm including an adjustably rotatable and extensible section, the head being pivotally supported on the extensible section and the thrust member being axially and rotatably movable in the head, a tensioned winding drum for the cable, a cam and clutch device for rotating the drum and the connections between the cable and thrust member including a pair of grooved wheels fixed on the upper end of the thrust member, a pair of auxiliary cables attached to the aforesaid cable and respectively attached to the two grooved wheels and wound thereon from opposite directions for imparting reverse directions of rotation to the thrust member and another auxiliary cable connecting the first named cable to the cam engaged with the thrust member.

9. In a chiropractic machine, a standard, a horizontal arm having a leg vertically and rotatably adjustable in the standard, a head adjustably carried by the outer end of the arm and a thrust member depending from the head, a cable operatively connected with the member for imparting a thrust and rotative movement thereto, and the body engaging part of the thrust member being detachably engaged with the latter, the horizontal arm including an adjustably rotatable and extensible section, the head being pivotally supported on the extensible section and the thrust member being axially and rotatably movable in the head, a tensioned winding drum for the cable, a cam and clutch device for rotating the drum and the connections between the cable and thrust member including a pair of grooved wheels fixed on the upper end of the thrust member and a pair of auxiliary cables attached to the aforesaid cable and respectively attached to the two grooved wheels and wound thereon from opposite directions for imparting reverse directions of rotation to the thrust member.

10. In a chiropractic machine, a standard, a horizontal arm vertically and rotatably adjustable in the standard, a head adjustably carried by the outer end of the arm, a thrust member depending from the head and rotatable and reciprocable therein, a cable extending through the

standard and arm, a manually operable tensioned drum at the lower end of the standard upon which one end of the cable is wound, and the other end of the cable having branch extensions operatively connected with the thrust member for imparting thrust and rotative movements thereto.

11. In a chiropractic machine, a standard, a horizontal arm vertically and rotatably adjustable in the standard, a head adjustably carried by the outer end of the arm, a thrust member depending from the head and rotatable and reciprocable therein, a cam engageable with the upper end of the thrust member, a cable extending through the standard and arm, a manually operable tensioned drum at the lower end of the standard upon which one end of the cable is wound, and the other end of the cable having branch extensions operatively connected with the thrust member and cam for imparting thrust and rotative movements thereto.

12. In a chiropractic machine, a standard, a horizontal arm vertically and rotatably adjustable in the standard, a head adjustably carried by the outer end of the arm, a thrust member depending from the head and rotatable and reciprocable therein, a cable extending through the standard and arm, a manually operable tensioned drum at the lower end of the standard upon which one end of the cable is wound, the other end of the cable having branch extensions operatively connected with the thrust member for imparting thrust and rotative movements thereto, the branch connections between the cable and

thrust member including at least two cables wound on the thrust member respectively in opposite directions and normally having slack therein, and said thrust member adapted to be manually rotated for placing one of the branch connections under the desired tension for varying the degree and controlling the direction of rotation of the thrust member during operation thereof.

13. In a chiropractic machine, a standard, a horizontal arm vertically and rotatably adjustable in the standard, a head adjustably carried by the outer end of the arm, a thrust member depending from the head and rotatable and reciprocable therein, a cam engageable with the upper end of the thrust member, a cable extending through the standard and arm, a manually operable tensioned drum at the lower end of the standard upon which one end of the cable is wound, the other end of the cable having branch extensions operatively connected with the thrust member and cam for imparting thrust and rotative movements thereto, the branch connections between the cable and thrust member including at least two cables wound on the thrust member respectively in opposite directions and normally having slack therein, and said thrust member adapted to be manually rotated for placing one of the branch connections under the desired tension for varying the degree and controlling the direction of rotation of the thrust member during operation thereof.

LEON A. POLITIS.
